UNITED STATES PATENT OFFICE.

ARTHUR F. L. BELL, OF SAN FRANCISCO, CALIFORNIA.

APPARATUS FOR REFINING PETROLEUM.

1,231,695.

Specification of Letters Patent.

Patented July 3, 1917.

Application filed May 10, 1916. Serial No. 96,568.

To all whom it may concern:

Be it known that I, ARTHUR F. L. BELL, a citizen of the United States, residing at the city and county of San Francisco and State 5 of California, have invented certain new and useful Improvements in Apparatus for Refining Petroleum, of which the following is a specification.

My invention relates to apparatus for refining petroleum in which the cracking is effected under high pressure within a still.

The object of my invention is to provide for a continuous operation of the process, said object being made possible and attained 15 by the continuous, automatic removal of the carbon which constantly forms on the inside of the pressure still when brought to the necessary temperature required for cracking purposes.

20 To this end my invention consists in means for continuously and automatically removing the carbon from the still walls, and directing it to a receiver for final disposition, without cessation of the cracking operation 25 carried out in the still.

In stills as commonly used in which oil is cracked under pressure, the accumulation of coke is such that it is not safe to operate the still on more than one batch of oil without 30 having to shut the still down, cool it off, and send men inside of it to clean and scrape it out before operating it again.

Even when oil is cracked under pressure in pipe retorts inside a furnace, as is also 35 the practice, a carbon is produced on the inside of the pipes which in a short time, so fills the coil with carbon that it becomes useless and has to be removed.

In some cases air is forced through the 40 heated coil, the idea being that the oxygen in the air will ignite the carbon and burn it out. The fact is however, that although combustion takes place, it only partly reduces the quantity of the carbon, burning the remainder 45 on the walls of the pipe, so that after a few operations the pipe is filled with a succession of layers of coke, which necessitates the removal of the coil.

In another practice the oil is generated 50 into vapor at the point of entrance to rotort tubes, so that instead of the retort being filled with oil it is filled with the vapors

which are cracked by coming in contact with the heated walls. Like the other processes, however, carbon builds up on the sides of the 55 retort; and although mechanical revolving devices with chains have been rotated inside the tube, they have not prevented the building up of excessive thicknesses of carbon on the inside walls of the retort to such a degree 60 that the retorts must be removed every few days, and the carbon taken out.

In the form of stills and retorts so far constructed, it is difficult to control the intensity of the heat radiating against the surfaces. The result is that certain parts of the retorts or stills are heated to a greater degree than others, with the effect that the parts receiving the greatest heat, become heated to such an extent that oxidation and 65 sluffing off of the surfaces of the steel, due to the affinity between oxygen and red hot steel, takes place; also there is a distortion of the metal on account of being heated to a point where the tensile strength of the heated 70 metal cannot sustain its shape against the internal pressure.

My invention contemplates a still construction in which a number of yielding or flexible scrapers are held firmly against the 80 surfaces and closely follow any inequalities thereof, thereby scraping off the accumulated carbon, and directing it to a reservoir chamber, from which it can be removed at the will of the operator, without stopping the 85 continuous distillation taking place in the still. I prefer to use a revolving still mounted on a hollow shaft revolving on trunnions, though my invention is not confined to this form, for it can be applied to 90 any form of vertical or horizontal still having a reservoir for the receiving of the removed carbon, which is guided to this reservoir by means of the yielding flexible scrapers.

I am aware that stirring and scraping devices have been used in stills for the purpose of keeping foreign substances or solids in suspense. My scraping devices do not answer this purpose, but due to their pressure against the surfaces which have accumulated a coating of carbon, they remove the coating and guide and direct it to a receiving reservoir, thereby allowing the 95 100

still to run continuously; or, at any rate, for a much longer period than would be possible where no scrapers had been used.

Referring to the accompanying drawings—

Fig. 1 is a longitudinal section of my improved still, showing it in its preferred form.

Fig. 2 is a cross section on the line 2—2 of Fig. 1.

Fig. 3 is a cross section on the line 3—3 of Fig. 1.

Fig. 4 is a sectional detail showing a modification in the reservoir chamber or receiver for the carbon.

Fig. 5 is a longitudinal section showing my improvements applied to a non-rotatable still.

Fig. 6 is a part cross section on the line 6—6 of Fig. 5 to show the scrapers.

Referring to Fig. 1, the brick foundation and furnace are indicated by 1, with burner 1'. 2 is the still preferably set at an inclination. The still has a hollow central shaft 3 which is mounted on trunnions 4, for axial rotation, by means of power transmitted through a gear 5.

The oil is supplied to the still from a suitable source, not shown, by means of a pump 6, the outlet pipe 7 from which communicates with the oil feed pipe 8 which enters the hollow shaft 3 of the still and delivers the oil thereinto, said oil then entering the still through holes 9 in said central shaft.

The distilled vapors enter the central shaft and pass therefrom into the vapor outlet 10.

I have not deemed it necessary to show the condenser connections of the vapor outlet, nor the receiving box for the condensed distillates and its connections, as these form no part of my invention. I have, however, shown a pipe 11 which serves to return to the oil feed pipe 8, such portion of the vapors as are not cracked, so that they may be again operated on in the still, and I also show by a pipe 12, that a small part of the oil may be used to lubricate the stuffing box at 13.

14 are scrapers. These may be in suitable number, extending along the length of the still at its lowermost portion, and in contact with its wall. The scrapers are independent of each other, and each is provided with two arms 15 which are pivotally hung at 16 upon a shaft 17 common to all. The shaft 17 is carried in the lower ends of ring hangers 18 which at intervals are journaled freely in suitable bearings 19 on the central shaft 3. Thus, though the still 2 and its central shaft 3 rotate, the scrapers hang free and act upon the inner surface of the still wall throughout its entire circumference as said wall rotates against them. Each scraper being itself pivotally hung by its arms has a flexibility adapting it to conform to in-

equalities of surface. The carbon removed by the scrapers is directed by them and by the inclination of the still, to the lower end. In order to remove the carbon thus directed and accumulating, there is secured to and revolving with the still at its lower end an arcuate scoop pipe 20, the outer open end of which lies in the circumference of the still, and its inner end opens into the hollow shaft 3, so that at each revolution said scoop pipe picks up the carbon and delivers it to the shaft. Secured to the shaft and communicating with it is the reservoir chamber 21, with a valved outlet 22.

23 is a flexibly supported pipe carried by 80 a pillar 24 and operated by a screw 25, to approach said outlet and form therewith a closing joint, as will be presently described.

The operation of the still as thus described is as follows:—Oil is supplied by the pump 85 6 to the still which is being rotated, through the feed pipe 8, and apertured hollow shaft 3, a portion of the oil being passed through pipe 12 to lubricate the stuffing box 13. The vapors pass out through the holes 9 into the 90 hollow shaft 3, past the transverse web supporting the inner end of pipe 8, through said pipe and up through the vapor outlet 10 to its condenser and distillate connections and are treated and disposed of in manner well 95 known.

As the cracking takes place in the still, more or less carbon is constantly deposited on the surfaces, which carbon is continuously scraped off by the flexible scrapers 14 and delivered to the lower end of the still, 100 where it is picked up by scoop pipe 20, which delivers it inside of the revolving shaft 3, and from there it finds its way to the reservoir chamber 21. When it is necessary to 105 remove the carbon which has accumulated in reservoir chamber 21, the still is stopped revolving for a few minutes and the flexible pipe 23 is forced up by the screw 25, so that it makes a tight joint on valved outlet 110 22. The valve of this outlet is then opened, and due to the pressure inside the still, all of the loose carbon is pushed out into pipe 23 for delivery to a receiving tank.

In some cases instead of using this form 115 of reservoir chamber 21, it might be desirable, as shown in Fig. 4, to extend the revolving shaft 3 into a stationary reservoir chamber 26, making the joint by means of stuffing box 27. In this manner it would 120 not be necessary to stop the revolving of the still, when necessary to empty the stationary chamber 26.

If it is desired to use a stationary still, such as 28 in Figs. 5 and 6, the method of 125 condensing will be the same as the revolving still, the vapors leaving the still by pipe 29 and the distillates returning for recracking by pipe 30, the fresh oil being pumped into the still by pipe 31. This still is 130

mounted in a brick setting in the ordinary manner, and the interior central shaft 32 is rotated through the gear 33. Attached to the rotating shaft and revolving with it 5 are the scrapers 34 arranged in helical series to guide the removed carbon to the reservoir chamber 35, from which as accumulated, said carbon is discharged from time to time. Each scraper is independently yieldable by 10 sliding on its arms 36, and is controlled by a spring 37. If a vertical or cheese box still is used, the scrapers will be so arranged as to guide the scraped carbon to a reservoir chamber in the center of the bottom of the 15 still.

It is obvious that my improvements are not confined to any form of still, nor to any form of scrapers nor receiving reservoir for the carbon, providing the arrangement be 20 such as to continuously scrape the carbon off and direct and guide it to the reservoir and dispose of it thence, all without interfering with the continuous operation of the still or with the process of distillation carried out 25 therein. But I prefer to use the revolving form of still, as this form permits better distribution of the heat over the surfaces, thereby not allowing one portion to become more heated than another, greatly reducing 30 the quantity of carbon deposited, by preventing over-heating, and reducing the possibility of distortion of the still or of undue oxidation.

I claim:

35 1. In petroleum refining apparatus, a longitudinally inclined still mounted for rotation on its axis; a non-rotating scraper within the still, acting in contact with its inner surface to remove the carbon therefrom; and a reservoir chamber in communication with the lower end of the still toward which the removed carbon is continuously advanced during the operation of the still.

2. In petroleum refining apparatus, a 45 longitudinally inclined still mounted for rotation on its axis; a non-rotating yielding scraper within the still acting in contact with its inner surface and automatically adjustable thereon, to remove the carbon therefrom; and a reservoir chamber in communication with the lower end of the still toward which the removed carbon is continuously advanced during the operation of the still.

3. In petroleum refining apparatus, a still 55 mounted for rotation on its axis; a series of independently yielding non-rotating scrapers within the still acting in contact with its inner surface and independently automatically adjustable thereon, to remove the carbon therefrom; a reservoir chamber communicating with the still; and means within the still to transfer the removed carbon to said reservoir chamber during the operation of the still.

4. In petroleum refining apparatus, a rotatable still having a hollow central shaft in its axis; a non-rotatable scraper suspended from said shaft and acting on the inner surface of the still to remove the carbon therefrom; a reservoir chamber in communication with the hollow shaft; and means within the still for transferring the removed carbon from the still to the hollow shaft during the operation of the still. 65

5. In petroleum refining apparatus, a rotatable still having a hollow central shaft in its axis, said shaft projecting from the still end; a non-rotatable scraper suspended from said shaft and acting on the inner surface of the still to remove the carbon therefrom; a reservoir chamber carried by the projecting end of the hollow shaft and in communication with its bore; and means within the still for transferring the removed carbon from the still to the hollow shaft during the operation of the still. 70 75

6. In petroleum refining apparatus, a still having a hollow, apertured, central shaft and mounted for rotation on its axis; means for supplying the still with oil through its hollow apertured shaft; means for carrying away from the still, through said shaft, the distilled vapors; a non-rotatable scraper suspended from said shaft and acting on the inner surface of the rotating still to remove the carbon therefrom; a scoop-pipe carried by the shaft and arranged to transfer the removed carbon to said hollow shaft; and a reservoir chamber in communication with the hollow shaft to receive the carbon therefrom during the operation of the still. 80 85 90

7. In petroleum refining apparatus, a still having a hollow, apertured, central shaft and mounted for rotation on its axis; means for supplying the still with oil through its hollow apertured shaft; means for carrying away from the still, through said shaft, the distilled vapors; a non-rotatable yielding scraper suspended from said shaft and in automatically adjustable contact with the inner surface of the still to remove the carbon therefrom; a scoop-pipe carried by the shaft and arranged to transfer the removed carbon to said hollow shaft; and a reservoir chamber in communication with the hollow shaft to receive the carbon therefrom during the operation of the still. 95 100 105 110 115

8. In petroleum refining apparatus, a still having a hollow, apertured, central shaft and mounted for rotation on its axis; means for supplying the still with oil through its hollow apertured shaft; means for carrying away from the still, through said shaft, the distilled vapors; a series of non-rotatable independently yieldable scrapers suspended from said shaft and in automatically adjustable contact with the inner surface of the still to remove the carbon therefrom; a 120 125

scoop-pipe carried by the shaft and arranged to transfer the removed carbon to said hollow shaft; and a reservoir chamber in communication with the hollow shaft to receive the carbon therefrom during the operation of the still.

In testimony whereof I have signed my

name to this specification in the presence of two subscribing witnesses.
